[57] **CLAIM**

The ornamental design for a combined oral jet cleaning housing and cover therefor, as shown and described.

DESCRIPTION

FIG. 1 is a front elevation of a combined oral jet cleaning housing and cover therefor, showing my new design;

FIG. 2 is a rear elevation thereof;

FIG. 3 is a side elevation thereof;

FIG. 4 is a side elevation thereof, with the movable cover in an open position;

FIG. 5 is a side elevation as seen from the side opposite FIG. 4;

FIG. 6 is a top plan view thereof;

FIG. 7 is a front perspective view thereof, with the movable cover in a closed position; and

FIG. 8 is a front perspective thereof, with the movable cover in an open position.

FIG. 1

FIG. 2

FIG. 3

FIG. 4

FIG. 5

FIG. 6

FIG. 7

FIG. 8
